US00D861161S

(12) **United States Design Patent** (10) **Patent No.:** **US D861,161 S**
(45) **Date of Patent:** ** *Sep. 24, 2019

(54) **CONNECTOR**

(71) Applicant: **KPR U.S., LLC**, Mansfield, MA (US)

(72) Inventor: **Wayne Schuessler**, St. Louis, MO (US)

(73) Assignee: **KPR U.S., LLC**, Mansfield, MA (US)

(*) Notice: This patent is subject to a terminal disclaimer.

(**) Term: **15 Years**

(21) Appl. No.: **29/608,556**

(22) Filed: **Jun. 22, 2017**

(51) LOC (12) Cl. **24-02**

(52) U.S. Cl.

USPC **D24/129**

CLAIM

The ornamental design for an connector, as shown and described.

DESCRIPTION

FIG. 1 is a perspective view of the connector showing my new design;

FIG. 2 is a front elevation view thereof, the rear elevation view being identical to the front elevation view;

FIG. 3 is a right side elevation view thereof, the left side elevation view being identical to the right side elevation view;

FIG. 4 is a top plan view thereof; and,

FIG. 5 is a bottom plan view thereof.

1 Claim, 5 Drawing Sheets
